UNITED STATES PATENT OFFICE

NELSON T. BRANCHE AND VILYNN O. BEAM, OF TOLEDO, OHIO, ASSIGNORS TO SURFACE COMBUSTION CORPORATION, OF TOLEDO, OHIO, A CORPORATION OF NEW YORK

DESIGN FOR A GAS-FIRED WARM AIR CIRCULATING HEATER

Application filed December 19, 1932. Serial No. 46,536. Term of patent 14 years.

To all whom it may concern:

Be it known that we, NELSON T. BRANCHE and VILYNN O. BEAM, residing at Toledo, in the county of Lucas and State of Ohio, have invented a new, original, and ornamental Design for Gas-Fired Warm Air Circulating Heaters, of which the following is a specification, reference being had to the accompanying drawing, forming part thereof.

Figure 1 is a front perspective view of the heater, showing my new design.

Figure 2 is a rear perspective view thereof, on a reduced scale.

We claim:

The ornamental design for a gas-fired warm air circulating heater, substantially as shown and described.

In testimony whereof we affix our signatures.

NELSON T. BRANCHE.
VILYNN O. BEAM.
